DESIGN FOR A BABY CRIB

Biagino Guastella, New York, N. Y.

Application May 10, 1946, Serial No. 129,543

Term of patent 3½ years

(Cl. D5—5)

To all whom it may concern:

Be it known that I, Biagino Guastella, a citizen of the United States, residing at New York, in the county of New York and State of New York, have invented a new, original, and ornamental Design for a Baby Crib, of which the following is a specification, reference being had to the accompanying drawing, forming a part thereof.

In the drawing:

Fig. 1 is a perspective view of a baby crib, showing my new design;

Fig. 2 is a top plan view of the same.

The opposite view to Fig. 1 is identical to the said figure.

I claim:

The ornamental design for a baby crib, as shown and described,

BIAGINO GUASTELLA.
